Primary Examiner — T Chase Nelson*Assistant Examiner* — Caitlin Mackenzie Williams(74) *Attorney, Agent, or Firm* — Bay State IP, LLC(57) **CLAIM**

The ornamental design for a packable sport cap, as shown and described.

DESCRIPTION

FIG. 1 is a front perspective view of a packable sport cap showing a new design;

FIG. 2 is a front view thereof;

FIG. 3 is a back view thereof;

FIG. 4 is a right side view thereof;

FIG. 5 is a top view thereof;

FIG. 6 is a bottom view thereof;

FIG. 7 is a front perspective view of the packable sport cap in a closed configuration;

FIG. 8 is a back perspective view of the packable sport cap in a closed configuration;

FIG. 9 is a left side view thereof;

FIG. 10 is a front view thereof; and,

FIG. 11 is a back view thereof.

The broken lines showing a cord lock and snaps depict portions of the packable sport cap that form no part of the claimed design. The remainder of the broken lines depict stitching, which does form part of the claimed design.

1 Claim, 9 Drawing Sheets(56)
